United States Patent Office

Des. 179,614
Patented Jan. 29, 1957

179,614

FASTENER

Daniel Francis Shafer, Mishawaka, Ind., assignor to Mishawaka Rubber and Woolen Manufacturing Company, Mishawaka, Ind., a corporation of Indiana

Application June 27, 1956, Serial No. 42,061

Term of patent 14 years

(Cl. D17—2)

Fig. 2.

Fig. 1 is a front view of the fastener and shows in dotted lines fragmentary portions of parts connected by the fastener; and

Fig. 2 is a view taken on the line 2—2 of Fig. 1.

The dotted line showing is for illustrative purposes only.
I claim:

The ornamental design for a fastener, as shown and described.
